J. G. POE

THROAT TUBE

Filed Nov. 7, 1921

WITNESS

H. Woodard

By

H. Williamson & Co Attorney

UNITED STATES PATENT OFFICE.

JAMES G. POE, OF DALLAS, TEXAS.

THROAT TUBE.

Application filed November 7, 1921. Serial No. 513,512.

To all whom it may concern:

Be it known that I, JAMES G. POE, a citizen of the United States, residing at Dallas, in the county of Dallas and State 5 of Texas, have invented certain new and useful Improvements in Throat Tubes; and I do declare the following to be a full, clear, and exact description of the invention, such as will enable others skilled in the art to 10 which it appertains to make and use the same.

This invention relates to an improved device to be used while operating and one object of the invention is to provide a device 15 which may be readily put in place and removed, one portion thereof being placed between the teeth and forming a prop to hold the mouth open while an anesthetic is being administered and the second portion 20 being passed through the prop element after the patient has been rendered unconscious by the anesthetic. By having the prop put in place before the person is anesthetized, the teeth are prevented from 25 contacting and the tube may thus be very easily put in place with its inner end portion extending into the throat.

Another object of the invention is to provide a device in which the tubular body 30 which is to be inserted through the prop into the throat will be provided with spaced longitudinally extending conduits which terminate at their outer ends in tube extensions curved towards the sides so that rubber tubes connected with these tube extensions 35 will not be bent and free passage through the tubes prevented.

Another object of the invention is to provide a device of the character described in 40 which the tubular body may have the conduits in spaced relation and this tubular body provided adjacent its inner end with a side opening communicating with the interior of the body between the conduits.

Another object of the invention is to provide a device which will be so constructed 45 that it will be firmly held in place by the teeth and will have no tendency to rotate and move out of the desired position.

Another object of the invention is to provide a device which will be cheap to produce, and which may be very easily cleaned and kept sanitary.

This invention is illustrated in the accompanying drawing, wherein:

Figure 1 is a view showing the device par-

tially in plan and partially in longitudinal section.

Figure 2 is a view showing the device in side elevation. 60

Figure 3 is a view showing the device in end elevation.

Figure 4 is a longitudinal sectional view through the device.

Figure 5 is a perspective view of the prop element.

Figure 6 is a sectional view through the prop element.

Figure 7 is a transverse sectional view through the tubular body. 70

This device includes a prop element to hold the mouth open and a tubular member which is to be passed through the prop element after the patient is unconscious. This prop element is provided with a tubular open ended body 1 which is flattened as shown so that it can be readily held between the teeth and will not have a tendency to turn or readily slip out of the desired position. A strap 2 which is formed of rubber will be placed upon the body 1 so that the device can be easily held without danger of the teeth being injured. This band 2 also serves to prevent the device from easily slipping as it permits of the device being firmly gripped. A collar 3 is provided at the outer end of the tubular body for engaging the lips or gums and preventing the prop from moving into the mouth beyond a desired distance. 90

The tubular member 4 which is to be passed through the prop and back through the mouth into the throat is provided with a collar 5 at its outer end for engaging the collar 3 and thus limiting inward movement of the tubular member 4 and preventing it from accidentally slipping through the prop and moving too far into the throat while an operation is being performed. This tubular member 4 conforms to the 100 shape of the flattened tubular body 1 and is provided with conduits 6 which extend longitudinally of the tubular member through the side portions thereof as shown in Figs. 1 and 7. These conduits extend 105 from the inner end of the tubular member to the outer end thereof and terminate in tube extensions 7 which extend forwardly from the outer ends thereof and are curved towards the sides. These tubes 7 have their outer end portions provided with enlargements 8 so that rubber hose 9 may be con-

nected with these tubes. A side opening 10 is provided adjacent the inner end of the tubular member 4 so that easy breathing will be permitted and danger of the inner end 5 portion of the tube being closed will be prevented.

When this device is in use, the prop will first be put in place and will be held between the teeth. The anesthetic will then be ad- 10 ministered until the patient is unconscious and the tubular member will then be passed through the prop and will have its curved inner end portion extending into the throat. With this prop in place, the tubular member 15 can be easily inserted without it being necessary to pry the teeth apart. A rubber hose leading from a bottle of vaporized ether may be connected with one of the tubes 7 and a rubber pipe leading from a vacuum 20 pump may be connected with the second tube 7. It will thus be seen that mucus and blood may be drawn out through one of these tubes 7 and the anesthetic administered through the second. The patient may 25 breathe through the main passage of the tubular member between the conduits 6. The opening 10 reduces the liability of this tube 4 being closed at its inner end. After the operation is completed, the device can be 30 easily-removed, the prop being left in place, until the patient gains consciousness.

I claim:

1. A device of the character described comprising a flat tubular body constituting 35 a jaw prop for insertion between the teeth to hold the mouth open, and an open-ended tubular member flattened to conform to the contour of the tubular body in cross section and slidale through said same for insertion 40 into the mouth and throat after a patient has been anesthetized with the prop in place between the teeth, the tubular member being held against rotation by the flattening of the tubular body and member.

2. A surgical device comprising a tubular 45 body constituting a jaw prop for insertion between the teeth to hold the mouth open, and a rigid open-ended tubular member curved longitudinally and slidale through the tubular body, said tubular body having 50 engagement with the tubular member to hold the same against rotation when positioned in the tubular body.

3. The structure of claim 2 having the tubular member provided with conduits 55 formed integral therewith and extending longitudinally through the same in spaced relation to leave a breathing space between the conduits, said conduits terminating in tubes extending from the outer end of the 60 tubular member.

4. The structure of claim 1 having the tubular member provided with conduits extending longitudinally through the same and terminating in tubes extending from the 65 outer end of the tubular member and curved towards the sides, the conduits being in spaced relation and the tubular member having one of its walls provided with an opening adjacent its inner end. 70

5. A surgical device comprising a tubular body provided with a side port adjacent its inner end and opening through the side of the body, and open-ended conduits extending longitudinally through the body with 75 the side port positioned between the conduits.

6. A surgical device comprising a tubular body provided with a side opening adjacent its inner end and opening through the side 80 of the body, and conduits extending longitudinally through the tubular body upon opposite sides of the side opening and terminating in tubes extending from the outer end of the body. 85

In testimony whereof I have hereunto set my hand.

JAMES G. POE.
